UNITED STATES PATENT OFFICE.

PAUL P. ALEXANDER, OF WORCESTER, MASSACHUSETTS.

SPARK PLUG.

Application filed October 14, 1920. Serial No. 416,888.

This invention relates to a spark plug, and the object is to provide means for producing an additional spark gap, in addition to that produced at or near the end of the usual bushing having communication with the engine cylinder.

A further object is to produce, in a spark plug, one or more spark gaps within or near the end of the bushing projecting into the engine cylinder, and an additional spark gap at the outer end of the plug, the electrodes being formed and mounted in a particular and novel manner, and being inclosed in a chamber the walls of which are transparent, permitting the operator to inform himself of the condition of the ignition system and to make any adjustment necessary by varying the gap between the electrodes.

A still further object is to provide in connection with an additional pair of electrodes, located within a chamber, the walls of which are transparent, means for permitting of the circulation of air within the chamber.

A still further object is to provide a particular form of cleaning device.

A still further object is to provide for mounting the lower electrode or electrodes within a tubular element which in turn is carried by a bushing threaded into the main bushing, said electrodes merging into a stem affording means for connecting the supplementary spark gap device to the plug per se, and constituting one of the terminals of the supplementary spark gap.

A still further object is to provide particular means for forming the chamber for the supplementary spark gap, and for mounting the outer or upper electrode.

With the foregoing and other objects in view, the invention consists in the novel construction, combination and arrangement of elements hereinafter described and claimed.

In the drawings, Figure 1 is a view of the plug in side elevation; Figure 2 is a vertical section; Figure 3 is a horizontal section, on line 3—3 of Figure 2; Figure 4 is a vertical section of another form.

The lower bushing, which in this instance will be termed a casing, is designated 10, and includes a threaded portion 11, for connection with the usual threaded opening for the spark plug in the cylinder wall. This casing 10 is further provided with a threaded portion 12 at its upper end, this being an internal thread and the exterior wall being of hexagonal form as illustrated.

A bushing 14 is provided with an exterior thread 15, cooperating with the internal thread just mentioned, and extending through this bushing 14, is an insulated element 17, constituting a stem and either terminating in the electrode 18, or serving to mount the latter. It is obvious that one or more contact points may be provided for cooperation with the cooperating electrodes, constituting the wall of the bushing. The inner electrode or electrodes just mentioned are preferably located at a reasonable distance within the bore of the bushing. The heat developed at this point is not therefore added to the normal heat of the cylinder, due to the explosion.

The stem 17 may be surrounded with insulation 16 of mica or other material, and a fiber washer or washers 20 surround this body of mica insulation. The hexagonal portion 21 serves the usual purpose of that form of exterior construction and a copper washer 22 may be located immediately below the hexagonal element.

The upper end of the stem 17 projects through a fibre disk 23 and is engaged by a nut 24, the end referred to acting or serving as one of the terminals of the additional spark gap. The stem 17 may be tapered, as shown at 25, in order to snugly fit the tubular member in which it is mounted.

An upper disk of fibre is shown at 27, and is spaced from the disk previously mentioned by tubes 28 through which the screws or threaded pins 29 pass, the heads of the pins engaging a metallic ring 30, and the lower ends of the pins engaging a metallic ring 32.

An insulating body 33 constituting a bushing is formed with the upper disk and upper metallic ring and receives the tubular member or sleeve 35, into which the upper electrode or terminal 36 is threaded. Means are therefore provided for varying the gap between the upper pair of electrodes, for purposes well known. A nut 37 surrounds the upper terminal, and likewise a thumb nut 38.

The supplemental or additional spark gap chamber is of particular importance, and is formed by the upper and lower disks spaced as indicated, the outer wall of the chamber being formed by a tubular transparent element 40, which is loosely retained between the upper and lower disks, permitting air to enter the chamber and adding to the effectiveness of the device. A blue flame high

tension spark is produced. The manner in which the various parts are insulated, where insulation is required, is of importance, and it may be noted that the structure providing the additional spark gap constitutes a part of the plug itself, and that the element passing through the tubular member of the intermediate bushing constitutes in effect a terminal for each spark gap.

10 In the form shown in Figure 4, the bushing 14' is provided with an enlarged bore 42, having a reduced end 43, and this bore receives the coiled spring 44 bearing against the shoulder formed by the reduced end, and bearing against a fibre washer 45. Other fibre washers 46, 47, are interposed between washer 45 and ring 32'. Within the bore 42 I mount a plunger 48 having a flanged end 49 cooperating with the seat 50 on the lower 20 end of bushing 14'. The stem 17' passes through the plunger and is rigid therewith, insulation being provided at 17'. The upper end of the stem extends into the supplemental spark gap chamber, as in the previous 25 instance, is secured by nut 24', and serves as one of the terminals for the additional spark gap.

On the suction stroke of the piston in the engine cylinder, the plunger 48 is drawn 30 inwardly against the action of the spring, and a small quantity of air rushes into the cylinder, but a sufficient quantity to effectively clean the terminals, and act in a certain degree as a cooling agent, prior to the

production of the spark, the effect of which 35 is increased, in view of the additional supply of oxygen. The individual parts of the plug can be replaced, thereby reducing to a minimum the cost of keeping the plugs in good 40 condition. Modifications in construction may be made within the scope of the appended claim.

What is claimed is:—

In a spark plug, including a stem for mounting a central electrode, upper and lower insulating disks, sleeves for spacing said disks apart, devices passing through said disks and sleeves for connecting the disks to form a chamber, a tubular member of transparent material mounted between 45 said disks and between the sleeves, the tubular member being shorter than the sleeves, providing space for the admission of air to the tubular member, and the stem projecting 50 into said member, an insulating body connected with the upper insulating disk, this disk constituting a flanged portion of the body and abutting the ends of the sleeves and extending across the end of the tubular 55 member, a threaded sleeve carried by the insulating body, an upper electrode threaded into the sleeve and cooperating with the upper end of the stem for forming a supplementary spark gap, and clamping devices carried by the upper electrode. 60

In testimony whereof I affix my signature.

PAUL P. ALEXANDER.
